UNITED STATES PATENT OFFICE

IRA M. WELLS, OF OAKLAND, CALIFORNIA

ROAD PLANER

Application filed March 4, 1930. Serial No. 433,039.

The invention is for a road planer, and has special reference to road surfacing devices.

The object of the invention is to provide a planer for roads specially adapted to the smoothing of ripples and bulges in a road surface.

Another object of the invention is to provide a device as outlined which will provide a smooth continuous plane surface on roadways formed of asphaltic or similar compositions without unnecessarily tearing up the surface.

A further object of the invention is to provide a device as described which is readily adjustable to the road surface and on which the cutting blades are easily removed and replaced.

A still further object of the invention is to provide a device as outlined which is conveniently manipulated, economically constructed and efficiently operated.

Referring to the accompanying drawings

Fig. 1 is a plan view of the invention mounted in a vehicle frame;

Fig. 2 is a longitudinal elevation of Fig. 1;

Fig. 3 is a plan view of the invention;

Fig. 4 is a longitudinal elevation of Fig. 3;

Fig. 5 is a sectional elevation taken on line 30 5-5 of Fig. 3.

The invention consists primarily of a supporting frame forming part of a vehicle, a planer frame suspended horizontally at three points within said supporting frame, standards integral with the supporting frame and having means for independently adjusting the planer frame at the different points of suspension, the planer frame being of stepped triangular form and having plate type cutters clamped to the stepped side faces.

Similar reference characters are used to designate similar parts throughout the several views.

A truck or vehicle frame 7 is provided with a wide bolster 8 and wheels 9, the frame 7 being so constructed as to hang close to the road surface 10. A draw bar or tongue 50 11 provides for attachment to a tractive de-

vice or for hitching of a team of horses thereto.

The planer comprises a substantially triangular frame 12, the vertex of the triangle forming the leading end of the planer. The 55 sides of the triangle are stepped in, as at 13 and have vertical faces 14 and cutter retaining recesses 15 forming thrust shoulders 32, tapped holes 16 being provided for reception of the bolts or studs 17. Hubs 18 60 are provided adjacent the vertices of the triangular member 12, and have apertures 19 for reception of the lift screws 20. Cutters 21 are made of sections of rectangular bar steel and are clamped to the surface 15 65 by means of clamps 22 which are drawn up by means of studs or bolts 17. Standards 23 may be made of structural sections, pipe or other rigid means with the lift screws 20 interposed and hubs 18 slidable therein. At 70 the upper end of standards 23, bearings 24 are provided for cooperation with lift screws 20 and bevel gears 25. Brackets 26 are integral with bearings 24 and have the integral bearings 27 disposed at approximate 75 right angles to the bearings 24. Shafts 28, rotatable in bearings 27 have affixed to one end the bevel pinions 29 and at the opposite ends the hand wheels 30. Pinions 29 and gears 25 are operated by means of the hand 80 wheels, the hubs of gears 25 being threaded to receive the lifting screws 20, the square heads 31 on the screws preventing rotation of the screws in hubs 18; therefore, when hand wheels 30 are rotated, pinions 29 drive 85 gears 25 which cooperate with the screws 20, thereby raising the frame 12 to clear the roadway or to suit special planing conditions. The apertures 19 are freely fitted to permit angular adjustment of the frame 12. 90 If desired, transverse apertures could be provided and yokes and eyes formed on the screws 20.

The operation of the device is as follows: 95 The planer cutters are placed in position and clamped by means of clamps 22 and cooperating bolts or studs 17. The frame 12 is adjusted to the desired pitch and depth by means of the hand wheels 30. The vehicle is then drawn along the roadway, the 100

cutters 21 shaving the top surface or ripples away and dragging along the sides of the triangular frame, filling holes and carrying the excess material beyond the heel of the frame and disposing the material at both sides. When the planing is completed, the frame 12 is lifted away from contact with the roadway by means of the hand wheels 30 and cooperating gears and screws.

10 It will be noted that variations in design, construction and arrangement of parts may be resorted to which are consistent with the spirit and scope of the appended claims, and that such variations will in no way detract from the scope or advantages of the invention.

I claim:

1. A road planer comprising a frame adjustably suspended in substantially parallel relation to a road surface, and provided with a plurality of plate type cutters in overlapping, stepped angular relation to the longitudinal axis of a supporting vehicle.

2. A road planer, in combination with a vehicle, a frame adjustably suspended in substantially parallel relation to a road surface, and a plurality of cutting edges removably attached to opposite sides of said frame in stepped relation and in overlapping diverging relation to the path of travel.

3. In combination with a vehicle, a planer frame suspended therein and adjustably related to the road surface, a plurality of plate type cutters removably attached to each side face of said frame and in stepped relation one to the other and overlapping in the direction of travel, said cutters on opposite sides being divergently related.

4. A road planer, comprising a frame with divergent stepped side faces, planer knives removably attached to said stepped side faces and overlapping in the direction of travel, and means for adjustably supporting said frame in operative relation to a road surface.

5. A road planer, comprising a frame of substantially triangular form, said frame being adjustably supported adjacent the vertices thereof in a vehicle, the sides of said frame consisting of a plurality of inwardly stepped faces in parallel relation, planer knives removably attached to said stepped faces, said knives being in angular overlapped relation relative to the travel of said vehicle.

6. A road planer, comprising a vehicle provided with a supporting frame, a planer frame of substantially triangular form adjustably supported in said supporting frame and relative to a road surface, planer knives removably attached to both sides of said frame, the knives on either side being disposed in stepped parallel relation to each other and angularly disposed relative to the knives on the other side, the knives on each

side forming an interrupted unbroken cutting plane in the direction of travel.

7. A road planer comprising a frame of substantially triangular form adjustably supported in a vehicle, said frame diverging rearwardly relative to the direction of travel of said vehicle and continuing with a plurality of inwardly stepped faces in parallel relation, planer knives adjustably mounted on said faces and in overlapped relation relative to parallelism with the longitudinal axis through said frame.

8. A road planer, in combination with a vehicle, a supporting frame, a planer frame of substantially triangular form with leading vertex and adjustably supported in said supporting frame relative to a surface, the divergent sides of said frame comprising a plurality of parallel stepped faces in overlapping relation relative to parallelism with the longitudinal axis through said frame, and planer knives removably affixed to said stepped faces.

9. A road planer, comprising a plurality of planer knives disposed on each side of a frame in stepped parallel relation, the knives on opposite sides being in angular relation, and the knives on each side being in overlapped relation relative to parallelism with a longitudinal bisecting axis between said knives on opposite sides, said knives being removably fixed to a frame, said frame being adjustably supported in substantially parallel relation with a road surface, a supporting structure for said frame, said supporting structure forming part of a vehicle.

10. A road planer, comprising two sets of planer knives in angular overlapping relation one to the other relative to the path of travel, the knives in each set comprising a plurality of inwardly offset parallel knives removably attached to a common frame, and means for adjustably mounting said frame in a vehicle in operative relation to a road surface.

11. A road planer comprising a frame provided with a plurality of divergent stepped faces, planer knives removably affixed to said faces, and means for adjustably mounting said frame in a vehicle in operative relation to a subsurface.

12. A road planer comprising a frame provided with a plurality of divergent stepped faces, planer knives disposed on said faces and extending below the bottom of said frame, shoulders on said faces for cooperation with the back of said planer knives, bolted clamps cooperating with said knives and said faces and means for adjustably mounting said frame in operative relation to a road surface in a vehicle.

13. A road planer comprising a frame provided with a plurality of divergent inwardly stepped faces and of substantially triangular form, planer knives fixed to said faces by means of clamps and depending from said

frame, the backs of said knives seating against thrust shoulders on said faces, adjustable supporting means adjacent the vertices of said frame and adapted to adjust said knives to operative relation to a road surface, and a supporting structure for said supporting means, said supporting structure forming a part of a vehicle.

14. A road planer, comprising two sets of planer knives in angular relation, each set comprising a plurality of knives in stepped parallel relation and in overlapping relation relative to parallelism with a bisecting axis between said sets of knives, a frame for said knives, clamping and retaining means for said knives, and means for adjustably supporting said frame in a vehicle in operative relation to a road surface.

15. A road planer comprising a multiplicity of paired equi-angularly divergent planer knives removably attached to a frame in overlapping relation relative to a bisecting axis and vertically disposed with depending cutting edges, said frame being adjustably supported at three points in a substantially horizontal plane in operative relation to a road surface, and a vehicle for support and operation of said planer.

16. In combination with a road vehicle, a planer frame of substantially triangular form adjustably supported at the vertices, in a substantially horizontal plane, a plurality of parallel faces formed in each side, each succeeding face being retracted, and plate type cutters removably mounted on said faces.

17. In combination with a road vehicle, a planer frame comprising a plurality of diverging sections forming a substantially triangular frame with stepped faces, plate type cutters removably secured to said faces and depending therefrom, said frame being adjustably supported by said vehicle in a substantially horizontal plane.

18. In combination with a road vehicle, a substantially triangular frame adjustably supported at the vertices, a plurality of parallel faces formed in each side, each succeeding face being retracted, cutters substantially coextensive with said faces and removably mounted thereon, said faces and cutters being so disposed as to provide a continuous cutting plane in the direction of travel.

In testimony whereof I have affixed my signature.

55 IRA M. WELLS.
